UNITED STATES PATENT OFFICE.

SIMON H. INGBERG, OF ELMHURST, ILLINOIS.

CONCRETE COLUMN CAP.

1,407,277.

Specification of Letters Patent. Patented Feb. 21, 1922.

Application filed May 21, 1920. Serial No. 383,072.

(DEDICATED TO THE PUBLIC.)

To all whom it may concern:

Be it known that I, SIMON H. INGBERG, a citizen of the United States, and a resident of Elmhurst, in the county of Du Page and 5 State of Illinois, have invented new and useful Improvements in Concrete Column Caps, of which the following is a specification.

I hereby dedicate this invention to the free use of the Government of the United States 10 and the public, and request the Commissioner of Patents to mark the patent, "Dedicated to the free use of the Government of the United States and the public."

My invention relates to the details used 15 for connecting columns and floor beams in timber building construction and has for its object to provide adequate and fire-resistive supports, in the form of reinforced concrete post caps, for connecting the columns of one 20 building story with those above or below, as well as to provide by the same means adequate and fire-resistive supports for the floor members framing into the caps near the columns.

In the accompanying drawings, which 25 form a part of this specification, Figure 1 is a longitudinal section through the center of the two-way reinforced concrete post cap taken on the line 1—1 of Figure 2;

Figure 2 is a cross section taken on the 30 line 2—2 of Figure 1;

Figure 3 is a section through a portion of a timber floor construction, taken at the face of the columns on the line 3—3, Fig. 2, showing the two-way reinforced concrete post 35 cap in place with reference to the other building members;

Figure 4 is an isometric view of the four-way reinforced concrete post cap.

Similar letters refer to similar parts 40 throughout the several views.

Referring to Figures 1, 2 and 3, the central slab, A, supports the columns B and B¹, on its lower and upper surface, respectively, and on the outer portions of its upper surface, 45 the floor beams, C. Portions of the load reactions from the beams, C, and the bending strains induced by them are transferred by shear to the outer ribs, D. The slab, A, and ribs, D, constituting the body 50 of the post cap, are made of Portland cement concrete or other suitable fire-resistive material having the required mechanical strength. The slab, A, is reinforced with the mats, E, and the ribs, D, with the mats, 55 F. The mats are made of metal rods or bars tied or welded together, or of woven,

welded or expanded metal mesh. The bars, G, are added to give the required rigidity to the reinforcing frame, prior to embedment in the body material of the cap. The 60 reinforcing frame is supported in a mold of the required shape, which is filled with the body material, preferably in one continuous operation. On hardening of the filling, the 65 reinforcing elements are firmly gripped and the two materials act in effective combination to resist the stresses and strains imposed on the cap by the beam and column loads.

Suitable recesses, H, are formed in the ribs, D, through which lag screws, I, (Fig. 70 3) are threaded into the column and beam ends to give added rigidity to the construction.

The four-way cap shown in Figure 4 is made to receive floor beams on four sides, 75 the ends of the beams being supported on the upper surface of the outer ends of the slabs, A¹. The columns bear against the lower and upper surfaces of the common central portion of the slabs, A¹, their ends 80 being contained within pockets formed inside of the ribs, D¹. The latter serve the same purpose as the ribs, D, of the two-way cap and the reinforcing details of the slabs and ribs are in effect the same in the four-way cap as described for the two-way cap.

By making the post caps of Portland cement concrete or other similar fire-resistive material, very little heat from a surrounding fire will be transmitted by the cap into 90 the beam and column bearings, and the latter will remain intact until the fire is extinguished or until the column fails due to impairment by fire outside of the cap. Under similar conditions the steel or cast iron 95 caps generally employed up to the present time in timber construction, will transmit enough heat to make the wood at the bearings soft and yielding, which results in failure at the bearing, due to cracking or slipping at the cap, before the fire-resistance of the column outside of the cap has been fully developed. The combination of design and material that obviates failure at the bearings in case of exposure of the cap to fire, is an 100 105 important part of my invention.

Having thus described my invention what I claim is:

1. In a cap for timber columns, the combination of intimately connected members of 110 Portland cement concrete or other similar fire-resistive material, consisting of a hori-

zontal slab for receiving the timber column and beam ends, vertical side ribs extending above and below said slab, connecting members extending below said slab and between 5 said ribs; and systems of reinforcing bars embedded in said slab, ribs, and connecting members.

2. In a cap for timber columns, the combination of intimately connected members of 10 Portland cement concrete or other similar fire-resistive material, consisting of a horizontal slab for receiving the timber column and beam ends, vertical side ribs extending above and below said slab, connecting members 15 below said slab and between said ribs; and systems of reinforcing bars embedded in said slab, ribs, and connecting members; said slab, ribs, and connecting members being adapted to be arranged above, below, 20 and at the sides of said timber column and beam ends, thereby protecting their timber

bearing surfaces against undue heating from a possible surrounding fire.

3. In timber building construction, the combination of timber columns and timber 25 floor members; a reinforced concrete column cap into which said columns and floor members are framed; said cap being formed of intimately connected members composed of Portland cement concrete or other similar 30 fire-resistive material and consisting of a horizontal slab, vertical ribs, intermediate connecting members, and systems of reinforcing bars embedded in said slab, ribs, and 35 connecting members; said slab, ribs and connecting members being arranged above, below and at the sides of said timber column and beam ends, thereby being adapted to protect their timber bearing surfaces against 40 undue heating from a possible surrounding fire.

SIMON H. INGBERG.
